Primary Examiner — Charles D Hanson(74) *Attorney, Agent, or Firm* — Dorsey & Whitney LLP(57) **CLAIM**

The ornamental design for a medical implant, as shown and described.

DESCRIPTION

FIG. 1 is a perspective view of a new design for a medical implant;

FIG. 2 is a right side elevational view thereof, the left side elevational view being a mirror image;

FIG. 3 is a rear elevational view thereof;

FIG. 4 is a front elevational view thereof;

FIG. 5 is a top plan view thereof; and,

FIG. 6 is a bottom plan view thereof.

The broken lines represent portions of the medical implant that form no part of the claimed design.
